UNDERSEA CAMERA HOUSING

Jerold S. Wollman and George F. Schmidt,
New York, N. Y.

Application September 20, 1957, Serial No. 47,795

Term of patent 3½ years

(Cl. D61—1)

Fig. 1 is a front view of an undersea camera housing, showing my new design.

Fig. 2 is an end view thereof.

Fig. 3 is a plan view thereof.

Fig. 4 is a rear view thereof.

We claim:

The ornamental design for an undersea camera housing, as shown.
